UNITED STATES PATENT OFFICE.

SAMUEL P. BUSH, OF COLUMBUS, OHIO, ASSIGNOR TO THE BUCKEYE STEEL CASTINGS COMPANY, OF COLUMBUS, OHIO.

SPRING SUPPORT.

Original application filed September 28, 1925, Serial No. 59,168. Patent No. 1,656,166, dated January 17, 1928. Divided and this application filed May 29, 1926. Serial No. 112,576.

This application is a division of an application Serial No. 59,168 filed by me September 28th, 1925, now Patent No. 1,656,166, granted January 17, 1928, the object of the 5 present invention being to provide a construction which will permit the side frame to be removed as a unit without materially disturbing the spring plank, springs and bolster in relation to each other, thereby reducing the 10 cost of changing wheels as well as the period during which the equipment is out of service. The invention is illustrated in the accompanying drawings and consists in certain novel features which will be hereinafter first 15 fully described and then more particularly pointed out in the appended claims.

In the drawings;

- Figure 1 is a plan view of a portion of a car truck embodying the invention,
20 Figure 2 is a side view of the same,
Figure 3 is a central transverse section,
Figure 4 is a detail of a key or removable stop lug.

The side frame 1 is shown with integral 25 journal boxes although the journal boxes need not be integral. The side frame has vertical columns which define a central opening 3 to receive the end of the bolster 4 and the springs 5 upon which the bolster end rests. In the bottom 6 of the side frame is a 30 pocket 7, and the end of the spring plank 8 is turned down, as at 9, to fit snugly in the pocket, the plank, of course, extending between and connecting the two side frames of 35 the truck. The springs rest upon a spring seat 10 which extends through the lower portion of the opening 3 and over the pocket 7 with one end fitting between the side flanges 11 of the spring plank, the spring seat being 40 formed with side flanges 12 to attain rigidity and strength. The flanges 11 terminate at the side frame and fit closely between the lugs or flanges 13 thereon, the interfitting engagement of the several flanges minimizing 45 the effects of the stress on the bend of the spring plank.

The weight of the spring is carried by the spring seat which, extending over the end of the spring plank, holds the plank firmly in 50 place. As a loaded car sways from side to side over uneven track, there is an unequal distribution of pressure upon the opposite ends of the group of springs when the bolster is tilted under a heavy side bearing load or

blow. The drawings show means for overcoming this inequality consisting of a rib or rocker 14 on the underside of the spring seat fitting in the pocket 7 and provided in its lower face with a transverse concavity 15 resting on a convex saddle 16 in the pocket, 60 the saddle constituting a fulcrum or pivotal support about which the angularity of the bolster will freely accommodate itself.

At the top of the central opening 3 in the side frame, in the sides thereof, are grooves 65 or reentrant recesses 17 which permit the frame to be passed over the end of the bolster, the projections 18 on the bolster passing through said recesses or grooves and the bolster being then lowered to rest on the 70 springs. The movement of the frame over the bolster is arrested by contact with the lugs 19 on the sides of the bolster which are preferably cast integral therewith. Under normal conditions of operating, the side 75 frames restrict the transverse movements of the bolster by contact with the inside stops 19 or the outside stops 20 arranged in spaced relation at each side of the bolster. The outside stops 20 are constructed as separate parts 80 and are held in a definitely spaced relation to the inside stops through direct interlocking with the bolster, preferably without the use of any third part, such as a bolt or rivet, for maintaining the relation.

The outside stop may have various forms and is shown as an L-shaped key adapted to fit with its horizontal arm in the groove 21 in the underside of the bolster and with its vertical arm between the side frame and the 90 lug 18 on the bolster. The grooves 21 at their inner ends are provided with recesses or notches for the upturned lugs 22 at the ends of the keys which serve to hold the keys in place. The keys are between the bolster and the springs and are held in place primarily by the weight or load carried by the bolster and springs. Heretofore, the opening 3 in the frame has been wider in its lower portion than in its upper portion to permit it to pass 100 over the outside column lugs of the bolster which construction required a relatively longer spring seat member on the frame. The relatively shorter length permitted by the construction herein set forth adds materially 105 to the strength of the device.

In car trucks of the usual construction, the bolster stops were generally not intended to

be removed for the convenience of dismantling the trucks, but were either cast integral with the bolster or secured to the same through permanent mechanical means. To facilitate assembling or disassembling of the trucks, the bolster opening was provided with an enlargement through which the outside bolster guides were free to pass after the side frame and bolster were brought into proper alignment and height relation with respect to each other by raising the side frame or lowering the bolster. In trucks having the journal boxes integral with the side frame, it necessitated the removal of springs, spring plank, and certain brake parts to bring the bolster into proper relation to the enlarged portion of the bolster opening before the side frame could be withdrawn.

With my improved construction, the grooves or recesses 17 at the top of the bolster opening 3 permit the frame to be passed over the end of the bolster, the projections 18 on the bolster passing through said grooves or recesses. The bolster is first slightly and easily lifted from the springs to release the keys or stops 20 and permit them to be withdrawn. After withdrawing the stops or keys, the bolster is again lowered to rest on the springs, whereupon the spring plank, with the superposed springs and bolster, is raised sufficiently to clear the interlocking engagement between the spring plank and the side frame. The side frame may then be moved sidewise away from the truck without materially disturbing the spring plank, springs, or bolster, thereby reducing the cost of replacing wheels or frames and expediting the work.

Having fully described my invention what I claim as new and desire to secure by Letters-Patent, is:—

1. In a car truck, the combination of a side frame having an opening therethrough to receive a bolster, a group of springs carried by the side frame in the said opening, a bolster having its end extending through the opening and resting on the springs, a lug on the side of the bolster abutting the inner side of the side frame, a lug on the side of the bolster beyond the outer side of the side frame and a key interlocking with the bolster and engaging between the last-mentioned lug and the outer side of the side frame.

2. In a car truck, the combination of a side frame having an opening therethrough to receive a bolster and provided with a transverse groove in the wall of said opening near the upper end thereof, a group of springs carried by the side frame in the lower end of the opening, a bolster having its end supported within the opening by the springs, the bolster being provided with a transverse channel in its bottom and with inner and outer lugs on its side, the outer lug being arranged to pass through the transverse groove

of the frame and the inner lug to abut the inner side of the side frame, and an L-shaped key engaging snugly between the outer side of the side frame and the outer lug on the bolster and in the channel in the bottom of the 70 bolster.

3. In a car truck, the combination of a side frame having an opening therethrough to receive a bolster and provided with a transverse groove through the wall of said opening near the upper end thereof, a group of springs carried by the side frame in the lower end of the opening, a bolster having its end supported within the opening by the springs and being provided with a transverse groove 75 in its bottom and with inner and outer lugs on its side, the outer lug being arranged to pass through the transverse groove of the frame and the inner lug to abut the inner side of the side frame, and key means engaging 80 snugly between the outer side of the side frame and the outer lug on the bolster and being held in place by the load carried on the bolster and springs.

4. In a car truck, the combination of side 90 frames comprising an upper and lower member and columns all cast integral and defining an opening between the columns, the columns being provided with transverse grooves in their opposed sides near the upper 95 member, a spring plank resting on the lower member and interlocking with the frame, springs above the spring plank, a bolster carried by the springs having its end passing through the opening, stops on the sides of the 100 bolster adapted to pass through the grooves in the columns, means cooperating with said stops to lock the frame and bolster against displacement of normal relation, said means being movable to an unlocked condition 105 whereby after disengaging the spring plank from the frame the latter may be removed leaving the bolster, spring plank and springs relatively intact.

5. In a car truck, the combination of a side 110 frame comprising an upper and lower member and columns, all cast integral and defining a bolster opening between the columns, said columns being provided with recesses on their inner faces and in their upper portion, 115 a spring plank resting on the lower member and interlocking with the frame, bolster springs above the spring plank, the bolster being carried by the springs with its end passing through the bolster opening, stops integral with the bolster at the inner side of the 120 columns, stops integral with the bolster on the outer side of the columns adapted to pass through the recesses in the columns when erecting or removing side frames and occupying a position below the recesses when in normal operating condition and whereby the bolster is interlocked with the side frames against displacement of normal relations.

6. In a car truck, the combination of a side 125

- frame comprising an upper and lower member, and columns connecting said members, there being a bolster opening between the columns and the columns having transverse grooves in their opposed sides near their upper ends, a spring plank carried by the lower member and interlocking with the frame, stop elements on the sides of the bolster arranged to pass through the transverse grooves in the columns, and means cooperating with said stop elements and the outer side of the side frame to lock the bolster to the side frame, release of said means and alinement of the stop elements with the grooves in the columns permitting withdrawal of the side frame without material disturbance of the normal relation between spring plank, springs and bolster.
7. In a car truck, the combination of a side frame having a bolster opening therethrough, a bolster constructed at its end to pass through said opening, fixed stops on the
- sides of the bolster at the outside and the inside respectively of the frame, and a removable stop outside the frame cooperating with the fixed stop outside of the frame and the side frame to lock the bolster to the side frame, said removable stop interlocking with the bolster whereby said stop will be held in place.
8. In a car truck, the combination of a side frame having a bolster opening, a bolster having its end fitted in the opening, an integral stop on the side of the bolster to abut one side of the side frame, a second integral stop on the side of the bolster at the opposite side of the frame, and a removable stop interlocked with the bolster and against the second stop to abut the adjacent side of the side frame.

In testimony whereof, I have signed this specification.

SAMUEL P. BUSH.
